ADJUSTING MEANS FOR HONING TOOLS

Kirke W. Connor and Albert Bleasdale, Detroit,
Mich., assignors to Micromatic Hone Corpora-
tion, a corporation of Michigan

Application October 7, 1935, Serial No. 43,932

9 Claims. (Cl. 51—184.3)

The present invention relates to cylinder grinding or honing tools, and more particularly to the mechanism for controlling the expansion and contraction of the abrading elements of such tools.

Principal objects of the present invention are to provide a honing tool having expandible and contractible abrading elements and embodying improved means to control the expansion and contraction of the abrading elements; to provide a honing tool having a grinding head rotatable and reciprocable with respect to a work piece throughout a working range and movable to a starting position outside of said range and embodying means to automatically move the grinding stones or abrasives into engagement with the work piece when the grinding head reaches a predetermined position within said working range; to provide a tool, as last stated, in which the control means for the grinding stones or abrasives is responsive to the relative movement between the grinding head and the work piece; to provide a tool, as last stated, in which the grinding stones or abrasives are retained in a retracted position during movement of the tool from the starting position to a predetermined point with respect to the working range; to provide a tool as last stated in which the abrasives are moved to work engaging position when the grinding head reaches a point within the working range.

Further objects of the present invention are to provide a honing tool embodying means for moving the tool grinding head from a starting position to a working position and for simultaneously rotating and reciprocating the grinding head within a working range, and embodying means responsive to the movement of the grinding head to the working position for moving the grinding stones or abrasives to work engaging position; to provide a honing tool as last stated embodying trip mechanism to control the movement of the grinding stones or abrasives to work engaging position when the grinding head reaches a predetermined point in a working range, and effective to thereafter retain said stones in the work engaging position during movement of the grinding head throughout the entire working range; to provide trip mechanism as last stated embodying a movable member effective at one limit of its movement to trip the grinding stones or abrasives into work engaging position and effective at the other limit of its travel to release the stones; to provide trip mechanism as last stated, embodying a member which is carried with the grinding head until it reaches one limit

of its movement, at which time the stones or abrasives are tripped to work engaging position; and to provide trip mechanism, as last stated, embodying a member resiliently supported upon and movable with respect to the supporting and guiding structure for the honing tool. 5

Further objects of the present invention are to provide a honing tool having a grinding head reciprocable with respect to a work piece throughout a predetermined working range, and embodying trip mechanism effective to move the grinding stones or abrasives to work engaging position when the grinding head reaches an intermediate point in said working range; to retain said grinding stones in said work engaging position throughout subsequent movement throughout said working range, and to thereafter release said stones to a retracted position when said grinding head is in an intermediate point in said range; to provide a honing tool as last stated, in which the trip mechanism is automatically controlled by counting mechanism and releases the stones to retracted position after a predetermined number of reciprocatory movements between the grinding head and the work piece; and to provide a honing tool in which the trip mechanism is responsive to the movement of and position of the grinding head with respect to the work piece. 10 15 20 25

With the above and other objects in view, which appear in the following description and in the accompanying claims, illustrative embodiments of the present invention are shown in the accompanying drawings, throughout the several views of which corresponding reference characters are used to designate corresponding parts, and in 30 35 which:

Figure 1 is a view in central vertical section of an illustrative embodiment of the present invention;

Fig. 2 is a view in horizontal section, taken 40 along the line 2—2 of Fig. 1;

Fig. 3 is a view in central vertical section of a modified embodiment of the present invention, providing a unitary trip mechanism for a bank or gang of honing tools; and 45

Fig. 4 is a view in elevation, partly in section, of an embodiment of the present invention in which both the tripping to abrading position and release to retracted position of the grinding stones or abrasives occur while the grinding head 50 is within a working range.

In its broader aspects, the present invention provides an improved honing tool, having a grinding head reciprocable over a predetermined range with respect to a work piece and embody- 55

ing means to trip the grinding stones or abrasives to a work engaging position when the grinding head reaches an intermediate point in the working range, and to thereafter retain the stones in such work engaging position during movement of the head throughout the entire working range. In a more restricted sense, the present invention is directed principally to supplementary structure, which may be used with various existing types of honing tools, to control the tripping and releasing of the grinding stones in the just stated manner. Several such conventional types of tools are illustrated in conjunction with the improved tripping mechanism of the present invention, and it will be understood that within the principles of the present invention various other types of honing tools may be used with the improved tripping mechanism, either in its illustrated or slightly modified form.

In one illustrated form, the improved tripping mechanism of the present invention is applied to a honing tool of the type described and claimed in the patent to F. J. Jeschke, No. 1,944,660, granted January 23, 1934, and assigned to the assignee of the present application. The patented structure comprises generally a grinding head and a driving head, which are universally interconnected. The grinding head carries a plurality of grinding stones or abrasives which may be moved automatically by tripping mechanism, from a retracted position to a work engaging position. The driving head is adapted for connection to a source of power, effective to simultaneously rotate the grinding head and reciprocate it with respect to the work piece throughout a predetermined range.

The tripping mechanism comprises generally tripping fingers extending radially from a portion of the tool for engagement by what may be called a tripping sleeve. When the grinding head and work piece reach a predetermined relative position, the tripping sleeve engages the tripping fingers and moves them radially of the tool to actuate the grinding stone to work engaging position, in which position the grinding stones are retained during the subsequent engagement of the grinding head and work piece with respect to each other. The actuation of the grinding stones to work engaging position occurs before the working range between the grinding head and the work piece is reached.

In accordance with the present invention, it is considered desirable to postpone the movement of the grinding stone to work engaging position until the grinding head and work piece are relatively positioned within the working range. Accordingly, the trip mechanism is so constructed that it is effective to trip the stones to work engaging position when the grinding head reaches an intermediate point in the working range with reference to the work piece, and to thereafter retain the grinding stones in the work engaging position during movement of the grinding head throughout the entire working range relative to the work piece.

In accomplishing this, the tripping sleeve is made movable with respect to the tool supporting structure, and at one limit of its movement is effective to trip the stone to work engaging position and at the other limit is effective to release the stones. The sleeve is carried between these positions by the engagement between it and the previously mentioned tripping fingers, and, preferably, the sleeve is resiliently supported and

thus urged to an intermediate position in its path of travel.

In a second illustrated form the present invention is applied to a honing tool of the type described and claimed in the patent to F. M. Kern, No. 1,944,662, granted January 23, 1934, and assigned to the assignee of the present application. Insofar as the present invention is concerned, the Kern structure distinguishes principally from the Jeschke structure in that the tripping mechanism comprises cam fingers carried by the tool and which, after having been tripped by a tripping cam stationarily supported, are retained in the tripping position by a pawl and ratchet construction. When the tool is withdrawn from the working range relative to the work piece, the tripping cam actuates the tripping fingers in an opposite direction, releasing the pawl and ratchet connection and permitting the stones to move to a retracted position.

In applying the principles of the present invention to a tool of this character, a tripping cam similar to that illustrated in the Kern patent may be used, and which is movable throughout a predetermined range by the movement of the honing tool. With this arrangement, during relative movement between the grinding head and the work piece to the working range, the tripping cam is carried with the tool until the grinding head reaches an intermediate point in the working range. At this point, the movement of the tripping cam is interrupted, thus rendering it effective to trip the stones into work engaging position. This tripping action also releases the tripping cam from the honing tool, permitting it to resume its initial position under the influence of suitable spring mechanism, and thus rendering it ineffective to again trip the tripping fingers until the grinding head is removed from the working range.

The just described embodiment also shows the application of the present invention to multiple honing units embodying a tripping cam common to the several honing tools. In the form illustrated, a single tripping plate having cam surfaces individual to the respective honing tools with which it is associated is movably supported upon a stationary part of the system, and is biased to an initial position by suitable spring mechanism. Movement of any of the associated honing tools is effective to carry the entire cam plate with it, the subsequent action of the cam plate being as described immediately above.

In accordance with a further feature of the present invention, the tripping mechanism is arranged to trip the stones to work engaging position when the grinding head reaches an intermediate point in the working range, retain the abrasive in such work engaging position throughout a predetermined working period, and then release the grinding stones to a retracted position at an intermediate point in the working range. With this arrangement, both the movement of the stones to work position and the retraction thereof from the work engaging position, occurs within the working range. In the form illustrated, a tool of the type described in the above identified Kern patent is utilized, and a tripping cam is provided for movement by the honing tool to tripping position, at which it is stopped, and in which position it is effective to trip the stones to work engaging position. This tripping action, as in the previously described embodiment, occurs when the grinding head is in a working range with reference to the work piece.

Mechanism is also provided responsive to the subsequent reciprocatory grinding movement between the grinding head and the work piece, and which may be called a counting device. This counting device, after a predetermined number of reciprocations between the grinding head and the work piece, is effective to move the tripping cam to a position in which it is effective to trip the stones to the retracted position upon the arrival of the grinding head at an intermediate point in the working range with reference to the work piece.

Considering the above embodiments in more detail and referring first to Figs. 1 and 2, a multiple assembly is illustrated as comprising a plurality of similar grinding tools designated generally as 10 and associated with illustrative work pieces 11. Each of the honing tools 10 may be, and preferably is, constructed in accordance with the previously mentioned Jeschke Patent No. 1,944,660 and is provided with a connector 12 through which it may be connected to a suitable external source of power effective to simultaneously rotate and reciprocate the tool. The illustrated tools 10 are adapted for internal grinding and are each provided with grinding heads 14 which carry a plurality of expandable and contractible abrasives or grinding stones 16. As described in more detail in the above identified Jeschke patent, the expansion and contraction of the stones 16 are controlled by a plurality of tripping fingers 18, disposed radially of the tool shank. Movement of the tripping fingers 18 to the positions illustrated in Fig. 1 loads suitable spring mechanism disposed within the tool body, which biases the stones outwardly into engagement with the surfaces of the associated work piece. Release of the tripping fingers 18, permitting the upper ends thereof to move outwardly of the tool body, permits the stones to be retracted within the head, out of engagement with the associated work piece.

The tripping fingers 18 of each tool are moved inwardly and outwardly under the control of a tripping sleeve 20, individual to the associated tool and which is guided within an outer sleeve 22, which may also be individual to the associated tool. A lower limit of travel for each sleeve 20 is provided by the engagement of the base thereof with an inwardly extending shoulder 24 formed near the base of the outer sleeve 22. A corresponding limit to the upward movement of each of the sleeves 20 is provided by a stop 26, threaded into the upper end of outer sleeve 22 and disposed in the path of the upper end of the associated sleeve 20. A compression spring 28, caged between a shoulder 30 formed in each outer sleeve 22 and an outwardly extending shoulder 32 formed at the upper end of each sleeve 20, biases the associated sleeve to its uppermost position.

The inner surface of each sleeve 20 is divided into an upper section 34 of enlarged diameter and a lower section 36 of reduced diameter, both sections being joined by a chamfered surface 38. The diameter of the enlarged portion 34 is large enough to receive the tripping fingers 18 in their outward or stone retracting positions. The diameter of the reduced portion 36 is such that the movement of the tool thereto moves the tripping fingers 18 inwardly of the tool and effects the previously mentioned expanding action of the grinding stones or abrasives.

When, in operation, a tool 10 is moved downwardly through its supporting frame members 23, the outwardly extending tripping fingers 18 there-

of pass freely through the enlarged portion 34 of the tripping sleeve 20. At a predetermined point in such movement, however, the tripping fingers 18 engage the sloping surface 38 within the sleeve 20. Continued movement causes the associated sleeve 20 to move downwardly simultaneously with the tool 10, the opposition of the supporting springs 28 associated with the sleeves 20 being overcome by the resistance to inward motion of the fingers 18.

When the tool 10 reaches the position corresponding to the position which the left-hand tool of Fig. 1 is illustrated as occupying, and which corresponds to an intermediate point in the working range thereof with respect to the work piece 11, the lower end of the tripping sleeve 20 engages the shoulder 24 in the outer sleeve 22, interrupting further downward movement of sleeve 20. Continued movement of tool 10, accordingly, causes the fingers 18 to be cammed inwardly by the surface 38, thus actuating the grinding stones 16 into engagement with the surface of the work piece 11.

In general operation, it may be expected that after such tripping action, the tool 10 will continue downwardly until the lower limit of its stroke is reached, and it occupies the position in which the middle tool of Fig. 1 is illustrated. During such continued downward movement of the tool the tripping fingers 18 slide along the surface 38 of the tripping sleeve 20. If, on the other hand, the movement of the tool is reversed immediately after the tripping action occurs, the upward movement of the tool will be accompanied by a corresponding upward movement of the sleeve 20, under the influence of the supporting springs 28 so that the fingers 18 will be retained within the reduced portion 36 of the sleeve 20 and the grinding stones 16 will be retained in engagement with the work.

If a tool 10 is withdrawn from its work piece 11, past the upper limits of its working stroke (right hand tool Fig. 1) such pull-out movement brings the upper end of the tripping sleeve 20 into engagement with the associated stop 26, interrupting further upward movement of the sleeve 20. Continued pull-out movement of the tool 10 thus slides the tripping fingers out of the sleeve 20 into the enlarged portion 34 thereof in which they are free to swing outwardly of the tool 10 and release the stones to a retracted position.

As best illustrated by the middle tool of Fig. 1 the length of each sleeve 20 is such that with the tool at its lowermost position and the associated sleeve at its uppermost position, the fingers 18 are still retained within the sleeve.

Throughout the operation of each of the tools 10 within the working range thereof accordingly, the tripping fingers 18 occupy positions along the surfaces 36 of reduced diameter within the associated sleeve 20 and the stones are thus held in work engaging position during the movement of the tool within the working range. The release of the stones from the work engaging position occurs automatically as stated above when a tool 10 is withdrawn to a point beyond its working range, bringing the associated sleeve 20 into engagement with its upper limit of travel, and thus releasing the fingers 18 therefrom.

It will be noted that in the just described embodiment, the tripping sleeves are individual to each of the honing tools 10, and it is thus possible to operate several tools entirely individually.

Referring more particularly to Fig. 3, an embodiment of the present invention is illustrated

utilizing tools which may be, and preferably are, of the type described and claimed in the above identified Kern Patent No. 1,944,662. In this embodiment a plurality of similar tools 50 are guided 5 within sleeves 52 which may either form part of or be suitably secured to the machine supports 54, and are provided with grinding heads designated generally as 56. As will be understood, the upper ends of the respective tools 50 are constructed to 10 cooperate with a suitable external source of power to effect a simultaneous rotation of the grinding heads 56 within the associated cylinders or other objects 58, and to simultaneously effect a reciprocation thereof within such cylinders. In Fig. 3, 15 for convenience, the left-hand tool is illustrated as occupying an intermediate or tripping position within the associated cylinder 58; the tool next to the left is illustrated as at the lower limit of its working range; the tool next to the right is 20 illustrated as at the upper limits of its working range; and the tool on the extreme right is illustrated as occupying a withdrawn or pull-out position, in which it may be disposed during adjustment of the tool or during a replacement of the 25 associated work piece 58, as will be understood.

As described in more detail in the above identified Kern patent, each of the tools 50 may be provided with tripping fingers 60 disposed in the path of and for actuation by tripping cams 62.

30 In the illustrated embodiment, all of the tripping cams 62 for the several tools form part of a common plate and are secured upon bosses 64 by studs 63. Bosses 64, in turn, are slidably supported upon standards 66 which may form part of or be secured to the machine frame 54. Compression springs 68, the opposite ends of which are seated between the upper surface of the frame 54 and the under surface of the bosses 64, surround standards 66, and bias bosses 64 to the illustrated 35 positions. With this arrangement, the tripping cams 62 are thus movable from the illustrated full line position to the illustrated dotted line position, in which they are stopped by the engagement of a collar 72 on each boss 40 with a collar 70 extending upwardly from the frame.

Engagement of any of the cams 62 by the associated fingers 60 during downward movement of the fingers 60 with respect to the cams, swings 45 the fingers 60 to the positions illustrated in Fig. 3. In this position the grinding stones or abrasives associated with the particular tool are biased to a work engaging position. The arrangement is such that after such tripping movement of each 50 finger 60, it is retained in the tripped and work engaging position of the stones, even though the tripping cam 62 thereafter be removed from the region of the finger 60. Engagement of any finger 60 by the associated tripping cam 62 during upward movement of the finger with respect to the cam rotates the finger in a clockwise direction as viewed in Fig. 3, releasing the stones to a retracted position in which they are out of engagement with the associated work piece.

60 With the arrangement of Fig. 3, the parts are so positioned that downward movement of any tool 50 from the loading position brings the finger 60 associated therewith into engagement with the associated cams 62 somewhat before the 65 upper limit of the working range of the tool is reached. The engagement between the finger 60 and cams 62 causes the cams 62 to move downwardly with the tool, the opposing force of the springs 68 being overcome by the resistance of the 70 finger 60 to tripping movement. At or about the 75

time the tool 50 reaches an intermediate point in its working range, as illustrated for the left-hand tool of Fig. 3, the tripping cams 62 reach their lower limit of travel. Continued downward movement of the tool 50 thus trips finger 60 to a work 5 engaging position of the associated grinding stones or abrasives. The tripping action between the cams 62 and the finger 60 also releases the cams 62, allowing them to rise to the normal and illustrated position under the influence of the 10 springs 68, in which position they are out of range of the associated finger 60 as long as the tool 50 is retained within the working range thereof. Accordingly, as long as the movements of the tools 50 are confined to the working range, as 15 shown for the left hand tool of Fig. 3, and the next two tools immediately adjacent thereto, the grinding stones or abrasives are retained in the work engaging position and the grinding action 20 may continue. If, however, a tool 50 is withdrawn from the work to the starting position shown for the right-hand tool of Fig. 3, such withdrawing movement brings the associated tripping finger 60 into engagement with the associated tripping cams 62, rotating the tripping finger in a clockwise direction as viewed in Figure 3, and releasing the stones to a retracted position, out of engagement 25 with the associated work piece.

Accordingly, it will be seen that in operating any of the tools of Figure 3 individually, or operating all of them as a unit, the downward movement thereof to a point within the working range automatically moves the stones to work engaging 30 position in which they are retained throughout the movement of the tool within such working 35 range. Withdrawal of the tool on the other hand, or tools, to a starting position retracts the stones out of engagement with the work.

The embodiment of the present invention shown in Figure 4 distinguishes principally in 40 function from the above described embodiments in that the retraction of the grinding stones from grinding position, as well as the movement thereof to grinding position, is effected while the grinding head is within its working range 45 with respect to the associated work piece. Referring particularly to Figure 4, a honing tool 50, which may and preferably does correspond in all respects to the tools 50 shown in Figure 3, is guided in a sleeve 52, forming part of or suitably 50 secured upon the honing machine frame 54, and is provided with a grinding head 56, adapted to be rotated within an illustrative work piece 58, and also reciprocated therein throughout a pre-determined working range, by suitable driving 55 mechanism connected at the upper end of the tool.

As also described in connection with Figure 3, tripping cams 62 are provided for cooperation with the tripping fingers such as 60, carried by 60 the tool. The tripping cams 62 are suitably secured as by studs 63 to bosses 64, which correspond to those described in connection with Figure 3, and one of which is illustrated in Figure 4. Each of the bosses 64 is slidably secured upon a 65 standard 66, which may form a portion of the supporting frame 54, and is normally biased to the illustrated position by the compression spring 68. A lower limit of travel for each of the bosses 64 and for the tripping cams 62 is provided by 70 the engagement between the collar 72 of each boss with a collar 70 extending upwardly from the base 54.

Each standard 66 also slidably carries a second collar 80, and retained thereon by a cap nut 82. 75

A crank 84 is suitably pivotally connected to each collar 80 by a pin 86, and is similarly pivoted to the outer end of one arm of a bell crank 88 by a pin 86. Each bell crank 88 is pivotally mounted by a pin 88 upon a standard 94 which may form part of or be secured to the machine base 54. The other and downwardly extending arm of each bell crank 88 is provided with an elongated slot, through which it is secured by a pin 96 to the outer end of a piston rod 98, conventionally reciprocable within a cylinder 100. The illustrative fluid pressure lines 102 and 104 admit fluid under pressure to the cylinder portions on the respective sides of the piston associated with rod 98, and the lines 106 and 108 perform a corresponding function in connection with a similar cylinder mounted at the opposite end of the complete machine assembly, and having a similar bell crank and collar assembly.

20 The lines 106 and 108 connect lines 102 and 104, and 106 and 108 to a suitable reversing valve 110, which may be common to all the tools of a complete unit, and disposed for actuation by any one of them. Valve 110 may be thrown to one operating position by a crank arm 112, and thrown to an opposite position by a ratchet 114. Ratchet 114 is disposed to be actuated around a step at a time by a pawl 116 carried upon a lever 118. Lever 118 is biased by a spring 120 to the position illustrated in Figure 4 but may be actuated to the illustrated dotted line position by the engagement therewith of the lower end of the grinding head 56 of the tool 50.

The actuating arm 112 is disposed to be thrown to the position illustrated in Figure 4 by a rod 122, which carries at its upper end a cam plate 124, lying in the path of the upper end of the tool 50. The upper end of rod 122 is guided within an opening formed in a bracket 126, secured to the top of the previously mentioned standard 66. A spring 128 is preferably provided to bias the cam plate 124 to the illustrated position. Suitable supply and exhaust lines for reversing valve 110 are designated 130 and 132.

45 Considering the operation of the assembly as a whole, the parts may be regarded as occupying a normal position, in which the valve connections are such as to retain bell crank 88 and collar 80 in their uppermost positions. Similarly, springs 50 68 maintain the supporting collars 64 and cam plates 62 in their upper positions.

Preferably, all tools of the unit are actuated simultaneously. The downward movement of each tool 50 with respect to the cam plates brings 55 the associated tripping finger 60 into engagement with a cam 62 somewhat before the upper limit of the working range of the tool is reached. Continued downward movement of each tool carries the cams 62 downwardly, the opposing forces of 60 springs 68 being overcome by the greater resistance to counter-clockwise rotation of the tripping fingers 60. This simultaneous movement of the tools and cams continues until the grinding heads reach substantially the midpoints of their working range, at which time the lower ends 72 of the supporting bosses 64 engage the upstanding collars 70, interrupting further downward movement of cams 62. This action effects a tripping movement of the fingers 60, in a counter-clockwise direction, resulting in a movement of the grinding stones of the tools to work engaging positions. The tripping action also releases cams 62, allowing them to rise to their initial positions under 75 the influence of the springs 68, and out of range

of the tripping fingers 60 as long as tools 50 are reciprocated within the working range thereof.

At each arrival of the grinding head 56 of the illustrated tool at the lower limit of its travel, it engages the valve arm 110, and notches the 5 ratchet wheel 114 one notch. After a predetermined number of such notching actions, representing a corresponding number of complete reciprocations of the grinding heads 56 within the associated work pieces 58, valve 110 arrives at 10 a reverse position, reversing the fluid pressure connections through lines 102 and 104, and causing the piston connected to rod 98 to move to the right as viewed in Figure 4. A corresponding reversal through lines 106 and 108 and the associated cylinder (not shown) occurs. This action rotates the bell cranks and moves collars 80 downwardly, carrying with them the supporting bosses 64. This action is effective to move the tripping cams 62 down to the initial tripping 20 position. Accordingly, upon the next arrival of the grinding heads 56 of the respective tools at or about the mid-point of their working ranges, the tripping finger 60 engages the tripping cams 62, and are rotated thereby in a clockwise direction, 25 releasing the grinding stones to a retracted position out of engagement with the work pieces 58.

Upon the arrival of the illustrated tool 50 at its starting or withdrawn position, the upper end thereof engages the under side of the cam plate 30 124, and moves it upwardly against the force of spring 128, carrying with it push rod 122 and swinging the valve operating arm 112 in a counter-clockwise direction, as viewed in Figure 4. This action, as previously stated, reverses the connections to valve 110 and consequently through lines 102 and 104 and 106 and 108 and causes the pistons connected thereto to return the auxiliary collars 80 to their initial positions. Thus, the supporting bosses 64 and the cams 62 resume 40 their illustrated positions under the influence of the associated biasing springs 68. At the conclusion of a grinding operation, accordingly, the parts are restored to their initial positions, in 45 readiness for further operation.

Although specific embodiments of the present invention have been described, it will be evident that various modifications in the form, number and arrangement of parts and in the detailed methods of practicing the present invention, 50 may be made within the spirit and scope thereof.

What is claimed is:

1. In honing mechanism comprising a tool having an abrading element movable between abrading and retracted positions to operate upon the 55 surface of an object, and adapted to be rotated and axially reciprocated throughout a predetermined working stroke relative to said object, the combination of a tripping finger carried by said tool for actuating said abrading element between 60 said abrading and contracted positions; a tripping plate; and means mounting said tripping plate adjacent the path of reciprocation of said tool for movement parallel to the axis of said tool, the range of movement of said plate being 65 such that said plate and finger are effective to cooperate to cause movement of said abrading element to abrading position when said tool reaches a point intermediate the ends of said working stroke, and to cause movement of said 70 abrading element to retracted position when said abrading element is moved relative to said object to a point in axially overlapped relation to said object but beyond the limits of said working 75 stroke.

2. In honing mechanism, comprising a tool having an abrading element movable between abrading and retracted positions to operate upon the surface of an object and adapted to be rotated and axially reciprocated relative to said object, the combination of a first adjusting means carried by said tool for effecting movement of said abrading element between said abrading and retracted positions; a second adjusting means for cooperation with said first adjusting means; means movably mounting said second adjusting means adjacent the path of reciprocation of said tool for engagement and movement by said first adjusting means; means limiting the movement of said second adjusting means, said first and second adjusting means cooperating at said limit to actuate said abrading element to abrading position; and additional means operable at the conclusion of a honing operation for moving said second adjusting means to cause said first and second adjusting means to cooperate to cause movement of said abrading element to retracted position.
3. In a honing machine, the combination with a plurality of honing tools, means whereby said honing tools may be rotated and reciprocated, a movable member cooperating with all of said tools for controlling the expansion and contraction of the abrading elements thereof, and means including hydraulic means for moving said member twice during a cycle of operation to first expand the abrading members of said tool and after the machining operation to contract said members.
4. In a honing device, the combination with a plurality of honing tools, means whereby said honing tools may be rotated and reciprocated, a cross member cooperating with said tools and movable independently thereof, means for supporting said member in a direction of the axes of said tools, means on said tools for effecting the expansion and contraction of the abrading elements thereof, and means cooperating between said member and tool expanding means for controlling the position of said abrading elements of all of said tools when said member is actuated, and means for actuating said member.
5. In a honing device, the combination with a plurality of honing tools, means whereby said honing tools may be rotated and reciprocated, a cross member cooperating with said tools and movable independently thereof, means for supporting said member in a direction of the axes of said tools, means on said tools for effecting the expansion and contraction of the abrading elements thereof, means cooperating between said member and tool expanding means for controlling the position of said abrading elements of all of said tools when said member is actuated, and a fluid operated device for actuating said member.
6. In a honing device, the combination with a plurality of honing tools, means whereby said honing tools may be rotated and reciprocated, a cross member cooperating with said tools and movable independently thereof, means for supporting said member in a direction of the axes of said tools, means on said tools for effecting the expansion and contraction of the abrading elements thereof, means cooperating between said member and tool expanding means for controlling

the position of said abrading element of all of said tools when said member is actuated, a fluid operated device for actuating said member, and timing means actuated through the reciprocation of said tool for controlling the extent of the machine operation.

7. In a honing device, the combination of a plurality of honing tools, means whereby said tools may be rotated and reciprocated, a pair of slides adjacent the endmost tools, a cross member carried by said slides, means for raising and lowering said member on said slides, and means cooperating between said member and tools for controlling the expansion and contraction of the abrading elements of said tool.

8. Honing mechanism comprising, in combination, a honing tool having an abrading element movable between an abrading and a retracted position, said tool being disposed to be reciprocated from a starting position to a working range at the beginning of a honing operation and thereafter during said honing operation to be reciprocated throughout said working range; a tripping element carried by said tool and actuatable to move said abrading element between said abrading and retracted positions; a tripping member mounted for movement relative to said tool between a tripping position in which it is effective to cooperate with said tripping element and a retracted position; means for normally retaining said tripping member in said retracted position; means for causing said tripping member to move to said tripping position as said tool is advanced from said starting position to said working range so as to actuate said abrading element to abrading position; and additional means for moving said tripping member to tripping position so as to cause said abrading element to move to retracted position.

9. Honing mechanism comprising, in combination, a honing tool having an abrading element movable between an abrading and a retracted position, said tool being disposed to be reciprocated from a starting position to a working range at the beginning of a honing operation and thereafter during said honing operation to be reciprocated throughout said working range; a tripping member adapted to co-act with said abrading element to effect movement thereof between said abrading and retracted position; means for normally retaining said tripping member in a retracted position; means mounting said tripping member so that movement of said tool from said starting position to a point within said working range is effective to carry said tripping member along therewith from said retracted position to a tripping position; means comprising a stop for said tripping member to interrupt said movement thereof and cause said tripping member to actuate said abrading element to abrading position when said tool reaches an intermediate point in said working range; and additional means co-acting with said tripping member to cause movement thereof from said retracted position into position to co-act with said abrading element to cause said abrading element to move to retracted position.

KIRKE W. CONNOR.
ALBERT BLEASDALE.

CERTIFICATE OF CORRECTION.

Patent No. 2,116,925.

May 10, 1938.

KIRKE W. CONNOR, ET AL.

It is hereby certified that error appears in the printed specification of the above numbered patent requiring correction as follows: Page 6, first column, lines 39, 52 and 65, claims 4, 5 and 6 respectively, after "member" insert the words for movement; and that the said Letters Patent should be read with these corrections therein that the same may conform to the record of the case in the Patent Office.

Signed and sealed this 5th day of July, A. D. 1938.

Henry Van Arsdale,

(Seal)

Acting Commissioner of Patents.
